CLAIM

The ornamental design for a camera mounting platform, as shown and described.

DESCRIPTION

FIG. 1 is a right side, rear, and bottom perspective view of the camera mounting platform showing my new design, the broken-line disclosure of a video camera, a protective glass and a battery box shown in FIG. 1 is for illustrative purposes only and forms no part of the claimed design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.
